UNITED STATES PATENT OFFICE.

ALPHONSO T. PALMER, OF CICERO, ILLINOIS.

RAIL-JOINT.

1,150,618.

Specification of Letters Patent.

Patented Aug. 17, 1915.

Application filed January 18, 1915. Serial No. 2,871.

To all whom it may concern:

Be it known that I, ALPHONSO T. PALMER, a citizen of the United States, residing at Cicero, in the county of Cook and State of Illinois, have invented certain new and useful Improvements in Rail-Joints, of which the following is a specification.

My invention relates to rail joints, and has for its object the provision of a simple and efficient joint of the character mentioned, which is very rigid, and one which may be easily and quickly adjusted to take up wear.

Other objects will appear hereinafter.

15 The invention consists in substantially the combinations and arrangement of parts hereinafter described, shown in the accompanying drawing forming a part of this specification, and more particularly specified 20 in the subjoined claims.

In the drawing, Figure 1 is a cross section of a rail joint embodying my invention. Fig. 2 is a perspective view of a wedge member used in the construction and shown on 25 a smaller scale than Fig. 1. Fig. 3 is a plan view of the wedge member shown in Fig. 2 but on a smaller scale. Figs. 4 and 5 are plan views of modified forms of wedges adapted for use in my rail joint.

30 My invention is adapted to be embodied in rail joints for joining rails of conventional patterns having the usual round holes at their ends. The rail ends are fitted in abutting relation.

35 My invention consists in the novel form of fish plates and tightening means employed in the joint.

In Fig. 1 I have shown a cross-section of a joint embodying my invention, one of the 40 rail ends not being shown since it is directly behind the rail end which is shown in section. Likewise, only one rivet 6 is shown, since the other rivets lie in a plane back of this rivet. It is understood that as many 45 rivets 6 may be used in forming the joint as is desired. The two fish plates 7 and their means for keeping them tight are the same, so that the description of one will suffice for both. The fish plate 7 has its upper edge formed angular, and is fitted against the lower surface 9 of the rail end 10 and extends downwardly a short distance on the web 11 of the rail ends. The lower portion of the fish plate has an 55 inwardly extending portion 12 which rests against the point where the web 11 and

flange 13 of the rail ends meet. With this construction then it will be seen that the central portion of the fish plate 7 is spaced from the web of the rail ends and engages the rail ends at the upper and lower edges of the webs thereof, also at the under sides of the heads of the rail ends. Rivets 6 pass through the central portion of the fish plates 7 and web 11 of the rail ends binding them together. I preferably use rivets 6 instead of bolts, as is the usual custom, and rivet the fish plates tightly against the rail ends, in order to insure the upper edges and the lower portions 12 of the fish plate always remaining firmly against the rail ends.

Along the lower edge of each fish plate 7, I provide a flange 14, which extends over the flanges 13 of the rail ends, and has its lower edge disposed substantially in a plane with the lower side of the rail ends. I provide a space between flange 14 and flanges 13 with the lower surface of flange 14 and its fish plate 7 meeting the upper surface of flanges 13 at an acute angle forming a wedge housing. In the wedge housing I provide a wedge formed of two parts 15 and 16. The part 15 has one of its longitudinal edges brought to a sharp edge and fitting the angular space between the lower edge of the fish plate 7 and the upper surfaces of flanges 13. The other part 16 of the wedge is adapted to substantially fit the remaining space of the wedge housing. The parts 15 and 16 have their adjacent edges disposed in substantially vertical planes and each formed substantially tapering longitudinally, in order to produce a lateral wedging action of the rail in the wedge housing. It will be seen from this construction, that upon moving the wedge part 16 relatively to the wedge part 15, the wedge part 15 will be forced inwardly toward the webs of the rail ends, and owing to the angular cross-section of part 15, the latter will produce vertical wedging action between the lower edge of fish plate 7 and the upper surfaces of flanges 13. The part 16 is preferably cut away at 17 and 18 to prevent the wedge part 16 contacting with the outer edges of the flanges 13 and portions adjacent said edges, so that when weight is applied to the rail ends, such as by a train passing over the rail ends, such weight will not be transmitted to the outer edge portions of the flanges 13, thereby relieving such outer edges of unnecessary strains.

I have shown several forms of wedge members which are equally adaptable to my rail joint. The form shown in Figs. 2 and 3 comprises two elongated parts 15 and 16, having their dividing surfaces 19 in substantially the same vertical plane with the exception of a short portion 20 at one end of the parts. This straight portion is preferably formed to prevent cutting through the thick edge 21 of part 16. In Fig. 4 I have shown a slight modification in which the part 22 has two inclined or wedging surfaces 23, one at each end. Adapted to co-operate with the wedging surfaces 23 are wedges 24. It will be seen with this form of wedge that each end may be adjusted separately, and at different tensions, if desired. In the form shown in Fig. 5, the wedge is made up of portions 25 and 26 having an irregular or zig-zag wedging surface 27 between them.

On the outer edges of flanges 14 are formed extensions 28 adapted to receive the spikes 29, in order to hold the joint in position on the railway tie 30. Under the joint may be provided a chair 31 of any ordinary or preferred construction. The form of chair shown is provided with upstanding ears 32 along its longitudinal edges, but these ears may be disposed of when so desired, since the wedge housings formed by flanges 14 and flanges 13 provide the complete mounting for the wedge members. With this construction, it will be seen that in case the flanges 14 were damaged and rendered inoperative from any means, the fish plates 7 would still be in such positions as to hold the rail ends in operative condition. In case of wear of the joint in use, it is only necessary to adjust the wedge parts 16 relative to the wedge parts 15, in order to re-adjust the joint to rigid condition.

While I have illustrated and described the preferred form of construction, I do not desire to be limited to the precise details set forth, but desire to avail myself of such variations and changes as come within the scope of the appended claims.

I claim:

50 1. A rail joint comprising a pair of rail ends having the usual heads, webs and flanges; fish plates engaging both of the rail ends at the junctures of the heads and webs of the rail ends, and at the junctures of the webs and flanges of the rail ends; rivets passing through said fish plates and rail ends; and wedges between lower portions of the fish plates and flanges of the rail ends providing wedging actions in both lateral and vertical directions between the fish plates and rail ends.

60 2. A rail joint comprising a pair of rail ends having the usual heads, webs and flanges; fish plates engaging both of the rail ends at the junctures of the heads and webs

of the rail ends, and at the junctures of the webs and flanges of the rail ends; rivets passing through said fish plates and rail ends; flanges on the lower edges of the fish plates extending over the flanges of the rail ends; and wedges between the flanges on the fish plates and the flanges on the rail ends producing both lateral and vertical wedging actions between the fish plates and rail ends.

75 3. A rail joint comprising a pair of rail ends having the usual heads, webs and flanges, fish plates engaging both of the rail ends at the junctures of the heads and webs of the rail ends, and at the junctures of the webs and flanges of the rail ends; rivets passing through said fish plates and rail ends; flanges on the lower edges of the fish plates extending over the flanges of the rail ends; and wedges between the flanges on the fish plates and the flanges on the rail ends producing both lateral and vertical wedging actions between the fish plates and rail ends, each of said wedges being made up of two parts disposed with their adjacent edges in vertical planes.

80 4. A rail joint comprising a pair of rail ends having the usual heads, web and flanges; fish plates engaging the rail ends at the under sides of the heads of the rail ends and at the meeting points of the flanges and webs of the rails; rivets passing through the fish plates and rail ends securing them together; flanges on the lower edges of the fish plates and extending over the flanges of the rail ends forming wedge housings; and wedges each made up of two parts and disposed in one of the wedge housings, the parts of each of the wedges having substantially vertical abutting surfaces arranged 100 for co-operative wedging action laterally between said parts.

85 5. A rail joint comprising a pair of rail ends having the usual heads, webs and flanges; fish plates engaging the rail ends 110 at the under sides of the heads of the rail ends and at the meeting points of the flanges and webs of the rail ends; rivets passing through the fish plates and rail ends securing them together; flanges on the lower 115 edges of the fish plates and extending over the flanges of the rail ends, the lower surfaces of the fish plates and flanges on the latter meeting the upper surfaces of the flanges of the rail ends at acute angles forming wedge housings; and wedges in said wedge housings, each of said wedges being made up of parts divided by substantially vertically disposed edges and adapted for relative longitudinal movement for producing vertical and lateral actions between the fish plates and rail ends.

90 6. A rail joint comprising a pair of rail ends having the usual heads, webs and flanges; fish plates having their upper edges 130

seated against the lower sides of the heads and extending downwardly a short distance on the webs of the rail ends and their lower portions engaging points of the rail ends 5 at the junctures of the webs and flanges thereof; rivets passing through the fish plates and webs of the rail ends; flanges on the lower edges of the fish plates and extending over the flanges of the rail ends, the 10 lower surfaces of the fish plates and flanges thereon meeting the upper surfaces of the flanges of the rail ends at acute angles forming wedge housings; and wedges in said 15 wedge housings, said wedges being made up of two parts, with one part having a substantially sharp longitudinal edge and fitted in the angular space between the lower edge of one of the fish plates and the upper surface of the flanges at one side of the rail 20 ends, and the other part of said wedge being adjustably fitted between the outer edge of said first mentioned part and the inner surface of the outer edge portion of the last mentioned fish plate.

7. A rail joint comprising a pair of rail ends having the usual heads, webs and

flanges; fish plates having their upper edges seated against the lower sides of the heads and extending downwardly a short distance on the webs of the rail ends and their lower 30 edges engaging points of the rail ends at the juncture of the webs and flanges thereof; rivets passing through the fish plates and webs of the rail ends; flanges on the lower edges of the fish plates and extending 35 over the flanges of the rail ends forming wedge housings; and wedges in said housings engaging the lower surfaces of the fish plates and flanges thereon and the upper surfaces of the flanges of the rail ends, the 40 wedges being cut away at their portions overlying the outer edges of the flanges of the rail ends and the upper surfaces of said flanges adjacent said outer edges.

In testimony whereof I have signed my 45 name to this specification, in the presence of two subscribing witnesses, on this 14th day of January A. D. 1915.

ALPHONSO T. PALMER.
